Primary Examiner — George D. Kirschbaum*Assistant Examiner* — Lillian Windham(74) *Attorney, Agent, or Firm* — William J. Clemens; Shumaker, Loop & Kendrick, LLP(57) **CLAIM**

The ornamental design for an operating and display panel for elevators, as shown and described.

DESCRIPTION

FIG. 1 is a front view of an operating and display panel for elevators showing our new design;

FIG. 2 is a front view of a second embodiment thereof; and,

FIG. 3 is a front view of a third embodiment thereof.

The broken lines in the figures show portions of the operating and display panel for elevators that form no part of the claimed design.
